UNITED STATES PATENT OFFICE.

JULIUS H. SERRA, OF WEST NEW BRIGHTON, NEW YORK.

CONCRETE WALL CONSTRUCTION AND BLOCK THEREFOR.

Application filed November 21, 1923. Serial No. 675,979.

This invention relates to improvements in concrete wall construction and blocks therefor.

One of the objects of this invention is to produce a concrete wall which will have great strength and rigidity, and which is particularly adapted for use in building tunnels, bridges and other structures where great strains are encountered.

Another object of my invention is to produce a wall composed of a series of units or concrete blocks that may be securely interlocked or keyed together in such a manner as to force the abutting portions of the blocks into close contact to secure rigidity of structure combined with great strength.

Another object of my invention is to produce a block which will not only have reinforcements which resist permanent strains encountered in a structure such as a tunnel, bridge or the like, but its reinforcement will resist temporary stresses such as encountered in the erection of such blocks.

Another object of my invention is to enable a wall composed of concrete blocks to be made water-tight.

Another object of my invention is to provide in a wall composed of concrete blocks a continuous reinforcement through a row of blocks and the joints therebetween.

Another object of my invention is to provide means to enable a series of rows of such blocks to be interlocked with each other or keyed together in a manner to force a close contact between the abutting surfaces of such rows, and also preferably to provide metallic reinforcing elements which traverse the block transversely and provide continuous reinforcing rods extending transversely through the blocks and having inter-row connections and reinforcements.

Another object of my invention is to provide each of a series of such blocks of a stack with a metallic caulking strip along the abutting edges of the blocks at the outer face thereof so that the joints between such blocks when stacked may be securely caulked with suitable caulking material for the purpose of making such joints water-tight, and for the purpose of reinforcing such edges to prevent chipping of the concrete during caulking.

Another object of my invention is to provide keying members between adjacent blocks which upon insertion will cause a tightening up of the joint between such

blocks and of the reinforcing elements embedded therein, and thus to increase the rigidity and strength of the structure.

Another object of my invention is to enable blocks to be set quickly and effectively in place and then to be locked to the adjacent block so as to facilitate the erection of walls for tunnels, bridges, buildings or like structures.

Another object of my invention is to provide a reinforcement in which the ends in adjacent blocks are so connected that a wall built therewith will be capable of taking care of stresses due to external loads and will be capable of taking care of strains of compression as well as strains of tension.

Another object of my invention is to provide means for grouting the keying apertures in a stack or wall under pressure.

Another object of my invention is to provide channel means communicating with such keying apertures for producing a grout seal in the joints.

Another object of my invention is to provide means for permitting the gripping device of an erector to take a secure and positive hold on the block and to prevent the chipping of the block by such erector gripping device.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a side elevation of a row of my improved reinforced concrete blocks connected together in a tunnel arch;

Fig. 2 is a longitudinal section of one of my improved blocks and portions of abutting blocks at opposite ends thereof;

Fig. 3 is a face or plan view of a wall section showing the connection of abutting blocks in a row and also the connection of blocks in adjacent rows;

Fig. 4 is an end elevation of an arcuate block embodying my invention;

Fig. 5 is a section on the line 5-5 of Fig. 2;

Fig. 6 is a section on the line 6-6 of Fig. 2;

Fig. 7 is a section on the line 7-7 of Fig. 2;

Fig. 8 is a longitudinal section on the line 8--8 of Fig. 4;

Fig. 9 is a disassembled view of a portion of the caulking strip;

5 Fig. 9^a is a perspective view of a fragment of a block showing the seating groove in which the strip shown in Fig. 9 seats at the edge of the block;

10 Fig. 10 is a perspective view of a key or tie bar for connecting the reinforcing members in the blocks together to interlock adjacent blocks in a row and adjacent rows together.

15 Referring now to these drawings, which illustrate a preferred embodiment of my invention, 1 indicates the body of a block which is usually composed of concrete and may be of any suitable form but which, in the embodiment illustrated, is arcuate in 20 conformation to enable the use thereof in tunnel construction, it being understood that these blocks may be utilized for any type of wall construction but are particularly adapted for tunnels, bridges and like structures 25 where strains of considerable magnitude are encountered.

30 In the preferred embodiment of my invention each of the blocks is provided with metallic reinforcing elements which form a unit in a metallic skeleton or frame work for a stack or wall, which skeleton or frame work has members extending transversely of each other, some of such members extending longitudinally of a row of such blocks to 35 reinforce the entire row, and other members extend transversely of the block to connect and reinforce abutting rows of blocks in a stack or wall. Thus a series of four longitudinal reinforcing rods 2 which, in the preferred embodiment, extend continuously through the block from end to end and have their ends flush with the ends of the concrete block and are so positioned that when the 40 said blocks are placed with ends abutting, the ends of the bars in abutting blocks will also abut against each other and form a continuing reinforcement in a row of such blocks. These longitudinal bars are preferably connected together intermediate their 45 ends within the block by bolts 3 to anchor the same securely together to further reinforce the block and space the said bars from each other so as effectively to resist any 50 strains due to driving of the key herein-after mentioned.

55 A series of similar bars 4 extend transversely of the block, as will be more particularly understood from an examination of Figs. 2 to 8 inclusive, and these transverse bars also preferably extend continuously 60 through the block and have their ends flush with the side surfaces of the concrete block and are so positioned that the ends thereof in abutting blocks in rows on opposite sides 65 will register and form a transverse frame

work. These rods abut when the blocks in adjacent rows are arranged with staggered joints, the abutting ends thus forming continuous reinforcements transversely of the first mentioned rods.

70 All of these reinforcing rods 2 and 4, as illustrated in the preferred embodiment shown, preferably have their adjacent abutting ends connected together and this connection is preferably made with a key or tie rod 5 which not only connects such reinforcing rods together but draws the blocks together to tighten the concrete joints between the blocks, and also tightens up the joints between the abutting rods to provide 75 a continuous reinforcing skeleton of bars, one series of bars extending longitudinally of the block through a row thereof, and the other series of continuous reinforcing rods extending transversely through the blocks 80 and through a series of rows thereof, thus forming a metal and preferably a steel interconnected frame work or skeleton in a stack of such blocks, each of the elements of which is not only tied or connected together but 85 tightened up so that the continuous skeleton or framing elements, which as aforesaid extend through the joints between the blocks, tighten and bring into close frictional contact the concrete abutting surfaces therebetween to make the stack or wall substantially waterproof and to cause the concrete blocks to form a rigid structure which will 90 resist both temporary and permanent strains of compression and tension, and also to provide an extremely rigid skeleton or frame that will further withstand strains of compression and tension of great magnitude.

95 This tightening up of the rods and joints between the blocks is effected by providing the reinforcing bars 2 and 4 and the keys or ties with interengaging parts, one or more of the walls and preferably both abutting walls of which is inclined to produce a wedging action. As illustrated, the bars are provided with locking notches 12 having inclined walls and each of the keys or ties is provided with wedging elements 5^a also having inclined walls 5^b adapted to engage the walls of abutting notches and draw the 100 bars and blocks firmly together. These keys, as shown, have a pair of such wedging elements adapted to engage two sets of notches in two sets of bars.

105 In order more effectively to waterproof the stack or wall, the joints are preferably caulked by any suitable caulking material, and in order so effectively to caulk without chipping the edges of the blocks, I provide at the outer edges of all the joints a caulking channel with metallic side walls. This is accomplished by reinforcing the abutting edges of each of the blocks along the outer face thereof with a metallic caulking strip. This enables a much tighter caulking of the 110 115 120 125 130

joints between abutting edges at the outer face of the wall than would otherwise be possible, and as illustrated I provide at such edges a metallic caulking strip 6 which, as shown, follows the contour of the edge of the block and has inwardly extending anchoring pieces 6^a which, as shown, are integral with the caulking strip and are embedded in the concrete block. These strips are set slightly back from the edge of the block to form caulking channels in the wall or stack between blocks in a row and between adjacent rows. It will be obvious that by driving a suitable caulking material into this channel between the caulking strips all the joints may be effectively caulked to seal up the wall and make the same waterproof.

In the preferred embodiment shown I also preferably provide in the face of each of the blocks a pair of grip apertures 7 for the purpose of enabling the gripping tongs of an erector to be inserted within these apertures for the purpose of picking the block up in the stacking or erecting operation. These grip apertures are preferably disposed so that their outer edges are aligned with the upper pair of longitudinally extending bars 2 and have relatively shallow grooves under each of such opposite bars in order that the prongs of the erector tongs when inserted within these apertures and spread, will take beneath the steel bars, thus avoiding injury to the block by the tongs and affording a ready and efficient means of gripping the same during erection.

One or more of the blocks are preferably provided with grout openings or bores 8 to permit grouting behind the wall in tunnel construction when desired.

In the preferred embodiment shown the ends of each of the reinforcing bars are preferably arranged within a socket or opening 9 through which the key or tie rod 5 is adapted to be inserted and when said tie rod is so inserted the sockets, which will register as aforesaid, are preferably filled with grout and in order to enable the nipple of the grout hose to be applied, I preferably provide adjacent the top of each socket with nipple notches 10, into which the hooks on the nipple may be inserted so as to permit the grout to be forced into the sockets 9 under pressure. I preferably also provide means for producing a grout seal in the joints and to this end I provide the surfaces of the block intermediate the ends of these sockets with grout channels 11 so that when the grout is forced through one socket it will pass through these abutting channels obviating the necessity of a separate grouting connection at every socket; and forming a grout seal between the abutting surfaces of the blocks.

In the preferred form of my block illustrated I preferably reinforce each corner

of the block adjacent to the keying apertures with metallic reinforcing rods 13 which preferably surround the aperture so as to reinforce the corners and furthermore prevent cracking of the concrete during the driving operation of the key.

In the arch construction shown in Fig. 1, I have, in the conventional manner, inserted a key block 14 between two three-quarter blocks on opposite sides thereof. It is obvious that this is merely one form of arch construction and that my concrete units or blocks may be used without the key block by inserting the blocks longitudinally of the arch construction.

Having described my invention, I claim:

1. A wall construction composed of units of plastic material, each having at its ends metallic reinforcing elements adapted to contact endwise and form butt joints with similar elements in abutting units, and means for frictionally and positively forcing the ends of such elements together to provide tight butt joints between the units and to provide a rigid metallic skeleton for each row of units.

2. A wall construction composed of units of plastic material, each having metallic reinforcing elements extending to opposite ends and also having metallic reinforcing elements extending to opposite sides thereof, said reinforcing elements being arranged to cause the ends thereof to form endwise contact and butt joints with the ends of similar elements in abutting units, and means for positively and frictionally locking both sets of reinforcing elements to abutting elements in adjacent blocks to provide tight butt joints between the units in a row and also between rows of units and furthermore to provide a rigid metallic skeleton for the wall.

3. A concrete block having reinforcing members comprising rigid bars provided with locking portions extending to opposite contact surfaces of the block and rigid wedging elements cooperating with such locking portions for frictionally and solidly locking such locking portions in abutting blocks to provide a solid butt joint therebetween.

4. A concrete block having a series of continuous reinforcing elements comprising bars extending longitudinally thereof and provided at their ends with locking portions having flat ends adapted to register and form butt joints with ends of similar reinforcing elements in abutting blocks in a row, and wedging elements for frictionally locking such ends together.

5. A concrete block having a series of continuous reinforcing elements comprising bars extending longitudinally thereof and provided at their ends with locking portions having flat ends adapted to register and form butt joints with similar reinforcing

elements in abutting blocks in a row, another series of similar reinforcing elements extending transversely of such longitudinal reinforcing elements and provided with locking portions having their ends adapted to register and form butt joints with ends of elements in abutting blocks in adjacent rows at opposite sides thereof, and wedging elements for frictionally locking such ends together.

6. A concrete block having metallic reinforcing elements comprising bars extending longitudinally therein and grip apertures having walls extending adjacent to said metallic reinforcements to enable an erector grip to take under such reinforcements.

7. A concrete wall composed of a series of units of plastic material each having metallic reinforcing elements extending to opposite contact surfaces of the block and provided with locking notches, the reinforcing elements in abutting blocks having their notched ends registering to form butt joints,

and an H-shaped keying element adapted to be driven through the locking notches in abutting blocks and provided with inclined surfaces to draw the ends of such elements and the abutting surfaces of the block together.

8. A concrete wall composed of a series of units of plastic material each having metallic reinforcing elements extending to opposite contact surfaces of the block and provided with locking notches having inclined walls, the reinforcing elements in abutting blocks having their notched ends registering to form butt joints, and an H-shaped keying element adapted to be driven through the locking notches in abutting blocks and provided with inclined surfaces to draw the ends of such elements and the abutting surfaces of the block together.

In witness whereof, I have signed my name to the foregoing specification.

JULIUS H. SERRA.
